UNITED STATES PATENT OFFICE.

COURTNEY HYDE, OF BROOKLYN, NEW YORK, ASSIGNOR TO RUSSEL DART, OF NEW YORK, N. Y., COURTNEY HYDE, OF BROOKLYN, NEW YORK, AND JOSEPH T. MONELL, OF JERSEY CITY, NEW JERSEY, COPARTNERS DOING BUSINESS AS ALPHADUCT COMPANY, OF JERSEY CITY, NEW JERSEY.

FLEXIBLE ELECTRICAL CONDUIT.

1,227,538.

Specification of Letters Patent. Patented May 22, 1917.

Application filed March 15, 1916. Serial No. 84,298.

To all whom it may concern:

Be it known that I, COURTNEY HYDE, a citizen of the United States, residing at Brooklyn, in the county of Kings and State 5 of New York, have invented new and useful Improvements in Flexible Electrical Conduits, of which the following is a specification.

My invention relates to flexible non-10 metallic electrical conduit, and has for its object the production of such a conduit which does not include as an element a supporting helix of semi-flexible material, and which possesses nevertheless the essential 15 characteristic of resistance to collapse when bent around curves or subjected to normal radial pressure.

The prime requisite of conduits of this 20 class that they shall preserve a circular form of cross section under all common conditions of use, has been known and recognized throughout the entire period of existence of the art, and heretofore a semi-25 flexible helical element disposed in various relations in such structures has been relied upon as the only available means for effecting this result. I have devised a conduit from which the semi-flexible helix is omitted and which nevertheless may be flexed or 30 subjected to radial compression without distortion of the circular cross section, which is more economical to manufacture, and which also embodies a smooth interior enabling the conductor to be fished with great ease.

35 My new and improved type of conduit consists of a longitudinally folded inner lining, a layer of waterproofing compound thereon, an outer braided jacket and a second layer of waterproofing compound.

40 The inner lining is formed of a strip of flat woven fabric embodying a weft of semi- flexible or resilient material as paper fiber, and a warp of soft or highly flexible material as cotton thread or yarn, folded longitudinally about a mandrel with the edges 45 abutting. The semi-flexible weft forms a series of rings which are closely bound or locked together by the warps and are adapted to resist radial compression and 50 tend to preserve an open duct when the conduit is flexed, that is, one that retains its cylindrical form on curves and bends or otherwise stated does not flatten or collapse

when bent in the course of installation of the same, when coiled for shipping or during the manipulation in the course of manufacture. In order to attain a circular cross section instead of a pear shape in a conduit of this description, I crimp or slightly fracture, without severing, the semi-flexible weft 60 of the flat fabric at two or more points adjacent the edges of the strip prior to forming the strip into a tube, with the result that a cross section of substantially circular form is maintained on completion of the 65 conduit. The mechanism by which this crimping operation is performed consists of a pair of specially shaped rolls through 70 which the fabric strip is fed during the progress of the material in the course of manufacture before the compound is applied as hereinafter more fully described together, with other parts of the process by which the product described is manufactured. The waterproof layers consist of any of the well 75 known compounds suitable to the purpose and familiar to this art. The braided cover is also of the type known to the art and may be applied by any preferred standard broiding machine.

80 In the accompanying drawing in which like numerals of reference indicate corresponding parts in the various figures thereof, Figure 1 shows a strip of the flat fabric for the inner tube or lining, and Fig. 2 a perspective of the same crimped or broken; Fig. 3 is a section of my new form of conduit on line 3—3 of Fig. 4 looking in the direction of the arrows; Fig. 4 a cross section of the conduit; Fig. 5 a detail of the 85 crimping rolls.

Referring to the drawing, 15 is the flat fabric lining strip composed of the semi- flexible, resilient transverse elements 7 and the flexible interwoven longitudinal elements 8. For the semi-flexible element 7, paper fiber or similar material is well adapted and cotton yarn is suitable for the flexible element 8. The dotted lines 9—9, Fig. 3, indicate the breaks in the fabric 15 which 95 tend to make the tube less pear shaped and approximately of the form shown in Fig. 4. 10 (Figs. 2, 3 and 4) indicate the edges which in the completed tube abut. If desired the inner tube may be reinforced at 100 the line of the abutting edges, by laying a

narrow strip 17 of thin material longitudinally over the joint, the strip being first compounded on one or both surfaces as preferred. 11 (Fig. 3) is the first compound 5 layer, 12 the braided jacket, 13 the second compound layer. 14 is a groove in the roll 19 (Fig. 5) into which the tongue 16 in the roll 18 projects when the parts are assembled in operative relation. The space between the surfaces of the tongue 16 and of the groove 14 should be limited sufficiently to jam the strip 15 as it passes and thus to bend or break the semi-flexible elements 7 without severing them. The proper adjustment of the rolls 18 and 19 to effect this purpose will depend upon the character of the particular fabric in use, and can readily be determined by experiment.

Suitable methods of making my product 20 will readily occur to those skilled in the art of manufacturing non-metallic flexible conduits for electrical conductors upon reading the preceding description of the invention. I suggest as a preferred method that 25 a narrow strip of material, such as 15, be first treated with waterproofing or other suitable compound, by applying a substantial coating to one side only of the strip, then forming the strip into a tube by folding it longitudinally, with the compound exposed, then covering it with a woven or braided cotton jacket, and then running the same through a bath of suitable compound and finishing the conduit with an application of mica, powdered soapstone or like 30 material to avoid a tacky or sticky surface.

It is obvious that these steps of manufac-

ture can be successively and automatically performed so as to manufacture an efficient conduit of the class referred to more economically than heretofore. 40

What I claim and desire to secure by Letters Patent is:

1. A conduit embodying a longitudinally folded layer of flat fabric composed of longitudinally extending flexible elements interwoven with transversely arranged semi-flexible elements. 45

2. A conduit embodying a lining of folded fabric composed of interwoven transversely arranged semi-flexible and longitudinally extending flexible elements, said semi-flexible elements being bent inwardly near their extremities. 50

3. A conduit embodying a tube composed of a series of rings of semi-flexible material interwoven with longitudinal members of flexible material. 55

4. In an electrical conduit, the combination of an inner tube consisting of a longitudinal folded layer of flat fabric composed of longitudinally extending flexible elements interwoven with transversely arranged semi-flexible elements, a layer of compound applied to the outer surface thereof, a jacket of textile fabric covering the same and an outer coating of compound. 60

In testimony whereof I have hereunto set my hand in presence of two subscribing witnesses, this 28th day of February, 1916.

COURTNEY HYDE.
